Primary Examiner — Robert M Spear*Assistant Examiner* — Ryan Harvey(74) *Attorney, Agent, or Firm* — Banner & Witcoff, Ltd.(57) **CLAIM**

The ornamental design for a cycle, as shown and described.

DESCRIPTION

FIG. 1 is a front, right perspective view of a cycle showing my new design;

FIG. 2 is a top view thereof;

FIG. 3 is a front view thereof; and,

FIG. 4 is a right side view, wherein the left side view of the cycle is a mirror image thereof.

The broken lines in FIGS. 1-4 are for environmental purposes only and form no part of the claimed design.

1 Claim, 4 Drawing Sheets(56)
